Fig. 1 is a front elevation of a ball point pen incorporating our new design;

Fig. 2 is a corresponding side elevation as seen from the right in Fig. 1;

Fig. 3 is a top plan view of the ball point pen shown in Fig. 2;

Fig. 4 is a transverse section taken substantially on the line 4—4 in Fig. 2, to show the configuration of the upper barrel portion, the interior thereof being indicated indeterminately for adaptation to a particular ball point mechanism;

Fig. 5 is a bottom plan view of the ball point pen shown in Fig. 2; and

Fig. 6 is a transverse section taken substantially on the line 6—6 in Figure 2, to show the configuration of

the upper barrel portion at the section line 6—6, the interior thereof being indicated indeterminately for adaptation to a particular ball point mechanism.

We claim:

The ornamental design for a ball point pen, as shown and described.
